UNITED STATES PATENT OFFICE.

EDWIN G. STAUDE, OF MINNEAPOLIS, MINNESOTA, ASSIGNOR, BY MESNE ASSIGNMENTS, TO UNITED STATES ENVELOPE COMPANY, OF SPRINGFIELD, MASSACHUSETTS, A CORPORATION.

ENVELOP-MACHINE.

1,147,762.

Specification of Letters Patent. Patented July 27, 1915.

Application filed November 12, 1912. Serial No. 730,887.

To all whom it may concern:

Be it known that I, EDWIN G. STAUDE, a citizen of the United States, and resident of Minneapolis, in the county of Hennepin, 5 State of Minnesota, have invented certain new and useful Improvements in Envelop-Machines; of which the following is a specification.

My invention relates to envelop machines 10 and particularly to the drying and stacking apparatus therefor.

The object of the invention is to provide a drier of very large capacity and one that is adapted for use with any size of envelop.

15 The invention consists generally in a continuously moving drier belt with means for delivering the envelops thereto.

Further the invention consists in means for adjusting the drier mechanism independently of the envelop feeding means.

Further the invention consists in various constructions and combinations, all as hereinafter described and particularly pointed out in the claims.

25 In the accompanying drawings forming part of this specification, Figure 1 is a plan view of an envelop machine with my invention applied thereto. Fig. 2 is a vertical sectional view of the drier, taken on the section line *w-w* of Fig. 3, Fig. 3 is a sectional view on the line *x-x* of Fig. 2, Fig. 4 is a sectional view showing the delivery mechanism, taken on the line *y-y* of Fig. 3, Figs. 5 and 6 are diagrammatic views illustrating the successive steps of the operation of the mechanism for feeding the envelops to the drier.

In the drawing, 2 represents that portion of the machine in which the preliminary creasing and folding operation of the envelop blank is performed, and 3 that portion of the machine in which the direction of movement of the blank is changed and the creasing and folding operation continued.

45 4 indicates the mechanism for gluing the flaps and 5 is that portion of the machine where the completed envelops are dried and stacked, this latter apparatus forming the subject-matter of my present invention.

50 Referring to Fig. 3, 6 represents a side bar of the machine frame, in which screw shafts 7 and 8 are mounted. On these screws brackets 9 and 10 are mounted and adapted to engage wheels 11 and 12 splined on shafts 55 13 and 14. Feed belts 15 and 16 pass around

these wheels and the revolution of the screw shafts 7 and 8 adjusts the wheels back and forth on their shafts to adapt the feed belts to envelops of different sizes. The loose flap of the envelop as it is fed toward the drier 60 is preferably engaged by a bar 17 which prevents the flap from being pressed down and stuck to the surface of the envelop. A rod 18 engages the edge of the flap and presses it inwardly over the envelop during the 65 feeding operation. The shafts 13 and 14 are capable of relative movement to allow the belt wheels to yield as the envelops pass between them. On the shaft 19 is a roll 20 that is adapted to coöperate with a roll 21 70 on the shaft 22.

23 is an arm loosely mounted on the shaft 22 and in the path of the cam 24 on the shaft 14, so that with each revolution of the shaft 14 the arm 23 will be rocked on its pivot. 75 Rolls 25 and 26 are mounted in the arm 23 and the roll 25 preferably has a jacket or sleeve 25' thereon of yielding material, such as rubber, which contacts with the surface of the roll 26. This jacket does not, however, extend the full length of the roll 25 and consequently a gap or opening is provided between a portion of the rolls 25 and 26 to allow the loose flap of the envelop to pass between the rolls without being subjected to pressure which might tend to stick the flap to the main portion of the envelop. Between the rolls 21 and 26 is a guide plate 27. As the envelops are fed between the rolls 20 and 21 and 25 and 26 80 85 the arm 23 will be rocked and the rolls 25 and 26 moved upwardly at a speed commensurate with that of the drier elevator, for the purpose of facilitating the delivery of the envelops to the drier, as will herein- 90 after appear.

28 and 29 represent screw shafts mounted in the frame 6 and supporting a rectangular frame 30. A shaft 31 is journaled in bearings in said rectangular frame and has one 100 end extending across the screw shaft 8 and provided with a worm gear 32 which meshes with a screw 33 that is splined on the shaft 14. The hub of the screw 33 has an annular groove 34 therein to receive an arm 35 secured to the frame 30. The shaft 31 is thus driven continuously from the shaft 14 and when the screws 28 and 29 are operated to move the frame 30 horizontally the worm 33 will slide on the shaft 14 and continue to 105 110

drive the shaft 31 in the different adjustments of the frame 30.

Mounted on the frame 30 are standards 36 forming an upright frame in which the envelop driver is supported. Sprocket wheels 37 are secured on the shaft 31 and a shaft 38 is journaled in bearings 39 in the upper portions of the standards 36 and is provided with sprocket wheels 40 connected with the sprocket wheels 37 by belts 41. The bearings 39 are provided with adjusting screws 42 by means of which the shaft 38 can be raised or lowered to tighten or loosen the belts 41, as the operation of the machine may require. The upper portions of the standards are connected and braced by a rod 43. Shafts 44 and 45 have cross-heads 46 supporting upright channel bar guides 47 in which the sprocket belts 41 are adapted to slide.

Journalized in bearings in the links of the belts 41 are a series of spindles 48 each having a crank 49 at one end, formed, preferably, by bending one end of the spindle out of line with the main portion thereof, the crank terminating in an end portion 50 parallel, substantially, with the spindle and adapted to slide in upright guide bars 51 which are secured to disks 52 and 53, preferably of cast metal having hubs mounted on the shaft 31 and bearing 39. The guide bars preferably have adjustable connections as at 54 with the disk 52 to permit vertical adjustment of the disk 52 with the shaft 38 and the sprocket wheels carried thereby.

The disks 52 and 53 have cam tracks 55 and 56 therein, the walls of which engage the ends 50 of the cranks to rotate the spindles a predetermined distance as they make the turn around the sprocket wheels at the top and bottom of the drier. Upon the spindles 48 carrier blades 57 are secured, between which the envelops are fed by the rolls 25 and 26. The belts 41 and blades 57 form an endless envelop carrier for the drier. The carrier blades move continuously instead of with a step by step motion, as usual in devices of this kind, and by tilting the delivery rolls 25 and 26 at a speed commensurate with that of the drier belt I am able to deliver the envelops, one at a time, to each carrier blade without any interruption in the motion of the belt. The drier thus has a much larger capacity and will handle a greater number of envelops in a given time than usual in devices of this kind.

Near the delivery rolls 25 and 26 I prefer to provide a guide plate 58 having an outwardly curved end contiguous to said rolls and carried preferably by a screw 59 that is adjustably mounted in the frame of the drier. Opposite the delivery rolls I prefer to provide a stop plate 60 supported in the path of the envelop as it is delivered

to the drier belt upon a pin 61 that is adjustably supported to allow movement of the plate toward or from the belt to adapt it for envelops of different length. Upon opposite sides of the drier belt I prefer to provide guide rods 62 and 63, arranged vertically near the outer edges of the carrier blades, the guides 62 being preferably supported by pins 64 which are adjustable in supports on the standards 36. The guide rods 63 have inwardly curved lower portions extending under the carrier belt and are preferably provided with ears 65 having slots 66 therein to allow for vertical adjustment of said rods on screws 67 and pins 68 which are adjustable horizontally in the drier frame. On each side of the carrier belt near the bearings of the spindles 48 I prefer to provide belts 69 upon which the inner edges of the envelops rest in making the turn over the top of the drier. These belts may be made of any suitable material. Parallel guides 70 are provided for the belts at the bottom of the drier, said guides having a horizontal portion beneath which the envelops are deposited by the carrier blades as they make the turn around the sprocket wheels at the bottom of the drier. The envelops are preferably discharged upon horizontal bars 71 which form continuations of the lower portions of the guide rods 63 and are carried preferably by a bracket 72 which is vertically adjustable on depending studs 73 and 74 to adapt the stacker for envelops of different width.

For the purpose of counting the envelops as they are delivered from the drier, I prefer to provide a star-wheel 75 mounted on a shaft 76 having bearings in the bracket 72, the prongs of the star-wheel being arranged to pass through recesses 77 provided in the outer edges of the carrier blades, the lower edges of the envelops contacting with the prongs of the star-wheel and rotating it step by step as the drier belt revolves. A disk 77' is geared to the shaft 76 to make one-half of a revolution with a certain predetermined number of complete revolutions of the star-wheel, for instance, fifty or twenty-five, as may be desired. The details of this counter device are not shown, as no claim is made to the same herein. The disk 77' is mounted near the ends of the carrier blades and is provided on its periphery with pushers 78 which move into contact with the end of an envelop at predetermined intervals to push the envelop endwise so that its opposite end will project beyond the stack or pile of envelops, as usual in counting devices of this nature. Near the opposite end of the carrier blades is a guide plate 79 supported by an adjustable pin 80 and movable therewith toward or from the ends of the envelops. This plate is provided with an offset 81 to receive the end of the envelop that

is projected by the operation of the pusher 78. A guide-plate 82 is also provided between which and the plate 79 the envelops are moved horizontally upon the bars 71 against a stop device 83, the bars 71 with the guide-plates forming a receptacle in which the envelops are stacked as they are discharged from the drier.

In the operation of the machine, the completed envelops with the loose flaps glued by means of the apparatus shown and described in my pending application filed Oct. 21, 1912, Serial No. 727,001, will pass out from between the feed belts 15 and 16 with the glue or gum on the loose flap only partially dried. The tilting rolls will receive the envelops from the feed belts and without applying any pressure to the loose flaps or causing them to come in contact at any point with the envelops, will deliver the envelops, one at a time, to the carrier blades, moving continuously past the delivery rolls 25 and 26. The drier belt is of sufficient height so that by the time the envelop has been carried up over the top of the drier and down to the bottom thereof, the glue on the loose flap will be sufficiently dry to allow the envelops to be stacked and pressed closely together. I have found the continuously moving drier belt a valuable addition to a machine of this character, for by its use I am able to dry the envelops as effectually as when the belt operates intermittently, and also greatly increase the capacity of the drier. By the adjustment of the screws 28 and 29 the entire drier can be moved horizontally to change its position with respect to the delivery rolls and adapt the machine for handling envelops of various sizes.

40 I claim as my invention:—

1. In an envelop machine, the combination with a traveling drying device, of feeding means operable to project envelops successively toward said device, and means for moving said feeding means for a limited distance in the direction of travel of said device during the delivery of each envelop thereto.

2. The combination, with a continuously moving drier belt, of feed rolls operating to deliver the envelops thereto, said feed rolls moving in the direction of movement of said belt during the delivering operation.

3. The combination, with upper and lower feed belts, of a continuously moving drier belt having carrier blades thereon and means interposed between said feed belts and said drier belt for positively delivering the envelops, one at a time, to said blades.

4. The combination, with the upper and lower feed belts, of an upright drier belt having carrier blades, said drier belt having a continuous movement, and means interposed between said feed belts and said drier belt and having a limited movement

with said belt to deliver the articles to be dried successively thereon.

5. The combination, with upper and lower feed belts, of an upright, continuously moving drier belt having carrier blades, delivery 70 rolls interposed between said feed belts and said drier belt, and means for tilting said delivery rolls in the direction of movement of said drier belt during the delivering operation.

6. The combination, with a feeding means, of an upright continuously moving drier belt having carrier blades, a pivoted bracket interposed between said feeding means and said belt, delivery rolls carried by said bracket and adapted to receive the articles from said feeding means, and deliver them successively to said carrier blades, and means for tilting said bracket to move said delivery rolls a predetermined distance in the direction of movement of said drier belt.

7. The combination, with the upper and lower feed belts and wheels and shafts therefor, of an upright, continuously moving drier belt having carrier blades, a pivoted 90 bracket, a cam mounted on one of said shafts and adapted to contact with said bracket to tilt the same, and delivery rolls mounted in said bracket and moved by the tilting thereof a limited distance in the direction of 95 movement of said drier belt.

8. In an envelop machine, the combination with a frame, of a traveling drying device supported thereby, a feeding means operable to project envelops into said device 100 in a direction substantially normal to its direction of travel, and means for adjusting said frame transversely with respect to the direction of projection of said feeding means, whereby to adapt said drying device 105 to different sizes of envelops.

9. In an envelop machine, the combination, with the upper and lower feed belts and envelop delivery rolls adapted to receive the envelops from said belts, of a frame, an 110 upright drier belt mounted in said frame, and means for adjusting said frame and drier belt lengthwise of said delivery rolls to adapt the drier to envelops of different sizes.

10. In an envelop machine, the combination, with a traveling drying device, of an envelop feeding means for delivering envelops to said drying device, means operatively connecting said drying device and 120 said feeding means for effecting their synchronous operation, and means for adjusting the relative positions of said drying device and said feeding means without changing the operative relation between them.

11. In an envelop machine, a drier comprising upper and lower shafts, sprocket wheels thereon, belts for said sprocket wheels, spindles having bearings in said belts, carrier blades mounted on said spin- 130

dles, means for rocking said spindles in their bearings to move said blades to an envelop carrying position, and means preventing the envelops from dropping down between said spindles as they pass over said upper shaft and sprocket wheels.

12. In an envelop machine, a drier comprising an upright belt having rocking spindles and envelop carriers mounted thereon 10 and flexible bands seated on said spindles on each side of said carriers and forming stops for the inner edges of the envelops.

13. In an envelop machine, a drier comprising an upper and lower shaft, sprocket 15 wheels mounted on said shafts and belts for said wheels, spindles having their ends journaled in said belts, each spindle having a lateral extension at one end forming a crank, blades mounted on said spindles between said belts, a guide-way wherein the ends of said cranks are slid able, said guide-way having upper and lower cam surfaces to engage said cranks and rock said spindles as they pass over said upper shaft and 25 sprockets and under said lower shaft and sprockets.

14. In an envelop machine, a drier comprising an upper and a lower shaft and wheels mounted thereon and a carrier belt 30 supported by said wheels, said upper shaft having vertically adjustable bearings, said belt including rocking spindles having crank arms at one end and carrier blades secured to said spindles, a guide-way for 35 said crank arms having a vertically adjustable upper section provided with a cam surface to engage said crank arms, the adjustment of said upper shaft and said upper guide section permitting a slackening or 40 tightening of said belt, for the purpose specified.

15. In an envelop machine, a drying device comprising an endless conveyer belt, having pivotally connected links, spindles

having bearings in said links, carrier blades 45 carried by said spindles, and means engaging said spindles for successively rocking said carrier blades to an envelop carrying position.

16. In an envelop machine, a drier comprising upper and lower shafts, sprocket 50 wheels mounted on said shafts and belts for said wheels, spindles journaled in said belts, each spindle having at one end a lateral extension forming a crank, envelop carriers 55 mounted on said spindles, a guide-way for said cranks, and means to engage said crank and rock said spindles, for the purpose specified.

17. In an envelop machine, the combination with a traveling drying device, of feeding means operable to project envelops successively toward said drying device, and means for imparting bodily movement to 60 said feeding means in a direction corresponding to the direction of travel of said drying device, coincident with the delivery 65 of each envelop thereto.

18. The combination, with a pair of feed 70 belts between which an envelop is moved forward and a continuously moving belt provided with blades forming a carrier for the envelops during the drying process, of an interposed transferring mechanism between said feed belts and said carrier, and 75 means for imparting an initial intermittent motion to said interposed transferring mechanism, whereby the latter is moved from a position to receive an envelop from said feed belts in a direction parallel with 80 the movement of said carrier.

In witness whereof, I have hereunto set my hand this 2d day of November 1912.

EDWIN G. STAUDE.

GENEVIEVE E. SORENSEN,
EDWARD A. PAUL.

It is hereby certified that in Letters Patent No. 1,147,762, granted July 27, 1915, upon the application of Edwin G. Staude, of Minneapolis, Minnesota, for an improvement in "Envelop-Machines," an error appears in the printed specification requiring correction as follows: Page 2, line 5, for the word "driver" read *drier*; and that the said Letters Patent should be read with this correction therein that the same may conform to the record of the case in the Patent Office.

Signed and sealed this 24th day of August, A. D., 1915.

[SEAL.]

J. T. NEWTON,

Acting Commissioner of Patents.
